Primary Examiner—T. Chase Nelson*Assistant Examiner*—Kathleen M Sims(74) *Attorney, Agent, or Firm*—James E. Howard; Andre Pallapies(57) **CLAIM**

The ornamental design for a utensil basket, as shown and described.

DESCRIPTION

FIG. 1 is a front perspective view from the top, right side of a

first embodiment of a utensil basket showing our new design;

FIG. 2 is a front view thereof;

FIG. 3 is a rear view thereof;

FIG. 4 is an enlarged top view thereof;

FIG. 5 is an enlarged bottom view thereof;

FIG. 6 is a left side view thereof;

FIG. 7 is a right side view thereof;

FIG. 8 is a front perspective view from the top, right side of a second embodiment of back-to-back utensil baskets showing our new design; and,

FIG. 9 is a front perspective view from the top, right side of a third embodiment of side-by-side utensil baskets showing our new design.

The broken lines represent environment or structure and do not form any part of the claimed design.
